UNITED STATES PATENT OFFICE

RICHARD C. LEAKE, OF ROCHESTER, NEW YORK, ASSIGNOR TO GENERAL RAILWAY SIGNAL COMPANY, OF ROCHESTER, NEW YORK

TRAIN CONTROL SYSTEM

Application filed February 27, 1930. Serial No. 431,769.

This invention relates in general to automatic train control systems, and has more particular reference to an electro-magnetic valve particularly adapted for use in such systems.

In train control systems such, for example, as disclosed in detail in the Reichard application S. N. 358,577 filed April 27, 1929, there is employed an electro-magnetic valve which, when energized, prevents an automatic application of the brakes, and when de-energized, vents the air line or equivalent part, to cause an automatic brake application.

One of the objects of the present invention is to provide an electro-magnetic valve, for train control systems, having an improved core structure and adjusting means therefor whereby to permit ready and accurate adjustment of the same.

Another object of the present invention is to provide an improved connection between an electrically operated spindle and the stem of a valve operated by such spindle, together with adjusting means for such connection.

A further object of the present invention is to provide improved armature stop means having improved adjusting means therefor.

Further objects, purposes and characteristic features of this invention will appear as the description progresses, reference being made to the accompanying drawings, showing, solely by way of example, and in no manner whatsoever in a limiting sense, one form which the invention can assume. In the drawings:—

Fig. 1 is a sectional side elevation of an embodiment of the invention.

Fig. 2 is a rear elevation of the invention.

Fig. 3 is a top plan view of the invention.

Fig. 4 is a fragmentary rear elevation of the invention with parts removed for clearness in the showing.

Fig. 5 is a longitudinal sectional detailed view of an adjusting cam member included in the invention.

Referring now to the drawings, and first to Fig. 1, there is here shown a support plate 1 which is furnished with bolt holes 2, for

bolts for clamping the plate to a receiving casing.

On the face of the plate 1, is a projecting lug 3 and below this lug 3 is an L-shaped bracket 4.

Carried in a threaded aperture in the lug 3, is a valve housing 5, having an inlet port 6 for connection to the air line or equivalent part of a usual air brake system, and exhaust ports 7 to atmosphere, communication between the stem 9 carrying a spring 10 for biasing the valve 8 to open position to allow communication between the ports 6 and 7.

Carried by roller bearings 11 and 12 respectively in the bracket 4 and the plate 1, is a spindle 13 to which is keyed a sleeve 14 carrying (integral or otherwise therewith) a sidewise projecting cuplike valve operating member 15 as clearly shown in Fig. 1. Within the cup member 15 is a plunger 16 contacting with the lower end of the valve stem 9, and forced toward the valve stem 9 by a spring 17 the tension of which can be readily adjusted by a threaded plug 18 which is accessible through an aperture 19 in the lower part of bracket 4, upward movement of plunger 16 within its cup 15 being limited by a transverse partition 20.

Spring 17 is considerably stronger than spring 10, whereby, in the position of parts as shown in Fig. 1, spring 17 overcomes the tendency of spring 10 to open valve 8 and hence maintains this valve closed to prevent venting the port 6 to atmosphere. On rocking of the spindle 13 in a direction to lower the cup 15, the end of plunger 16 is moved downwardly away from the end of valve stem 9 to allow spring 10 to open the valve 8 and vent the air line to atmosphere. The possible angular rocking movement of spindle 13 is so small, as described just below, that the plunger 16 cannot move out of operative alignment with valve stem 9, the contacting surfaces of 16 and 9 sliding on each other.

On the rear face of plate 1 is carried the electro-magnetic structure for operating the spindle 13 and its associated parts. Fas-tened to the spindle 13, is an armature 21

which can rock at each end between cam adjusting stop posts 22, and upstanding spaced legs 23¹ of a stop bracket 23, adjustable in position by the post 22. In this manner, the extent of rocking movement of spindle 13, is very limited. The armature is under the influence of two U-shaped cores 24, each carrying two energizing coils 25, and are fastened, as by means of screws 25¹, to support saddles 26, with the saddles in turn fastened to the rear face of plate 1, as by screws 27.

The armature and core structure is preferably of laminated construction, to minimize electrical losses, and the brackets 23¹ and saddles 26 are of brass or other non-magnetic material, as also is the plate and its various support lugs and brackets.

Carried on the plate 1, are terminal posts 28, for connection of lead-in wires, (not shown).

As best shown in Fig. 4, the armature 21 under the influence of the cores 24, operates at each end between the upstanding legs 23¹ of the stop bracket 23 and the adjusting and stop post 22. Each bracket 23 is adjustable by means of a cam 29, on the corresponding post 22, whereby to give an adjustment of this bracket in any direction parallel to the plate 1, this adjustment being permitted by means of oversized openings 30 in the bracket 23, through which pass the clamping and fastening screws 31.

A like adjustment is provided for each of the saddles 26, by their cam adjusting members 22¹, each having a cam 29¹ and operating to adjust the saddle 26 in exactly the same manner as the bracket 23 is adjusted; here again the adjustment being permitted by the oversized openings 30¹ through which pass the clamping screws 27.

An additional adjustment is provided for the saddle 26, by means of screws 32 carried in lugs 33 fixed on the plate 1, the ends of screws 32 bearing against rear faces 34 of bosses on the saddle, whereby to give an adjustment of the saddle at right angles to the length of the armature.

With the various adjusting means described above, it is readily possible to bring the pole faces 24¹ of the cores 24 to be exactly parallel with the co-acting faces of the armature when in attracted position, and also to adjust the stop saddle 23 so that its stop arms 23¹ space the armature in energized position at a short distance out of contact with the pole faces, so as to perform the function of usual residual pins.

The entire structure, as described above, operates in a manner which should now be readily apparent. When the coils 25 are energized, the parts assume the positions shown in the drawings, with the armature 21 against the stop arms 23¹ so as to rock the spindle 13 to bring the operating plunger 16 against the lower end of stem 9 so as

to close the valve 8, whereby to prevent venting of the port 6 to atmosphere.

On de-energization of the coils 25, the valve spring 10 moves valve stem 9 downwardly to open the valve 8 and vent the port 6 to atmosphere, and in rocking the spindle 13, it moves the armature 21 to its de-energized position in which it bears against the cam adjusting stop posts 22.

The above rather specific description of one form of this invention, is given solely by way of example, and is not intended, in any manner whatsoever, in a limiting sense. Obviously, the invention can assume various different physical forms, and is susceptible of numerous modifications, and all such forms and modifications, as come within the scope of the appended claims are intended to be covered by this application.

Having described my invention, I now claim:—

1. In a valve for automatic train control systems, in combination, a support plate, a spindle pivoted in the plate, a valve housing on the plate, a valve in the housing, a stem on the valve, biasing means for biasing the valve to open position, a cup member carried by the spindle, a separate spring pressed plunger in the cup member with one end bearing against the stem on said valve for operating the valve, and electro-magnetic structure for operating the spindle.

2. In a valve for automatic train control systems, in combination, a support plate, an L-shaped arm on the plate, a spindle pivoted in the plate and arm, a projecting lug on the plate, a valve housing adjustably held in the lug on the plate, a valve in the housing and biased to open position, a cup carried on a sleeve keyed to the spindle, an adjustably spring pressed plunger in the cup with one end bearing against a stem on said valve for operating the valve, and electro-magnetic structure on the plate for operating the spindle.

3. In a valve for automatic train control systems, in combination, a plate, a valve and valve housing on the plate, a spindle pivoted in the plate and positioned to operate said valve, an armature fixed to said spindle, and a support saddle positioned adjacent each end of the armature and at opposite sides thereof respectively, screw and slot means for clamping the saddle to the plate, a U-shaped core detachably mounted on the saddle, a pivoted pin passing through the saddle and plate, and a cam on the pin cooperating with a cam receiving opening for adjusting the saddle relatively to the plate.

4. In a valve for automatic train control systems, in combination, a plate, a valve and valve housing on the plate, a spindle pivoted in the plate and positioned to operate said valve, an armature fixed to said spindle, and a support saddle positioned ad-

- 5 jacent each end of the armature and at opposite sides thereof respectively, screw and slot means for clamping the saddle to the plate, a U-shaped core detachably mounted on the saddle, a pivoted stop pin passing through the saddle and plate, a cam on the pin cooperating with a cam receiving opening for adjusting the saddle relatively to the plate, a stop bracket clampable to the plate by pin and slot connections, an upstanding stop arm on the bracket lying in the path of movement of the armature, and a pivoted cam pin for adjusting the bracket with respect to the plate.
- 10 5. In a valve for automatic train control systems, in combination, a plate, a valve and valve housing on the plate, a spindle pivoted in the plate and positioned to operate said valve, an armature fixed to said spindle, and a support saddle positioned adjacent each end of the armature and at opposite sides thereof respectively, screw and slot means for clamping the saddle to the plate, a U-shaped core detachably mounted on the saddle, a pivoted stop pin passing through the saddle and plate, and a cam on the pin cooperating with a cam receiving opening for adjusting the saddle relatively to the plate, an upstanding boss on the saddle, a lug on the plate, and a screw in the lug and bearing against the boss for further adjustment of the saddle on the plate.
- 15 6. In a valve for automatic train control systems, in combination, a plate, a valve and valve housing on the plate, a spindle pivoted in the plate and positioned to operate said valve, an armature fixed to said spindle, a support saddle positioned adjacent each end of the armature, and at opposite sides thereof respectively, screw and slot means for clamping the saddle to the plate, a U-shaped core detachably mounted on the saddle, a pivoted pin passing through the saddle and plate, and a cam on the pin cooperating with a cam receiving opening for adjusting the saddle relatively to the plate, a stop bracket clampable to the plate by pin and slot connections, an upstanding stop arm on the bracket lying in the path of movement of the armature, and a pivoted cam pin for adjusting the bracket with respect to the plate, an upstanding boss on the saddle, a lug on the plate, and a screw in the lug and bearing against the boss for further adjustment of the saddle on the plate.
- 20 7. In a valve for train control systems, in combination, a support plate, a spindle pivoted in the plate, a valve operable by the spindle, an elongated armature fixed at its center to the spindle, U-shaped magnetic cores respectively at opposite sides of the two ends of the armature pin and slot means for clamping the cores in position on the plate, cam adjusting means for each core, a stop bracket at each end of the armature, cam means for adjusting the brackets on the plate, and spaced upstanding stop arms on each bracket positioned adjacent the ends of the cores.
- 25 8. In a valve for train control systems, in combination, a support plate, a spindle pivoted in the plate, a valve operable by the spindle, an elongated armature fixed at its center to the spindle, a U-shaped magnetic core at each of opposite sides of the two ends of the armature, pin and slot means for clamping the cores in position on the plate, cam adjusting means for each core, a stop bracket at each end of the armature cam adjustable on the plate and having spaced upstanding stop arms positioned adjacent the ends of the core, and a double set screw adjustment for each core.
